UNITED STATES PATENT OFFICE.

FRANCIS KING, OF LOS ANGELES, CALIFORNIA.

OPHTHALMIC MASSAGE INSTRUMENT.

Application filed March 25, 1926. Serial No. 97,212.

My invention relates to an ophthalmic massage instrument that is especially designed for imparting pressure, suction, and vibratory massage movement to the eye ball 5 for the treatment of various optical troubles and irregularities such as near-sightedness, far-sightedness, astigmatism, muscle imbalance, inflamed and congested eyes, or in fact any irregular condition of the eye 10 that will lend itself to scientific treatment with the aid of vibratory or massaging movement, the pressure or suction of a fluid medium such as air or water and the beneficial action of radioactive material.

15 The principal objects of my invention are to provide a relatively simple and practical instrument that may be readily used by patients for self-treatment; to provide an ophthalmic device of the character referred 20 to that may be used after the manner of an ordinary eye cup for the purpose of treating the front portion of the eye ball with water, either pure or containing healing agents; further, to construct the device so 25 that it may be partially collapsed or contracted in order that the water or liquid contained within the device will exert pressure against the front portion of the eye ball for the treatment of certain irregular 30 conditions; and further, to provide a device that may be readily rotated for the purpose of imparting to the eye ball and its muscles a beneficial vibratory movement or massage.

35 With the foregoing and other objects in view, my invention consists in certain novel features of construction and arrangement of parts that will hereinafter be more fully described and claimed and illustrated in the 40 accompanying drawing, in which—

Fig. 1 is a perspective view of an ophthalmic instrument constructed in accordance with my invention.

Fig. 2 is a section taken lengthwise 45 through the center of my improved instrument and showing the applicator applied to an eye ball, the latter being illustrated in dotted lines.

Referring by numerals to the accompanying drawings which illustrate a practical embodiment of my invention, 10 designates a hollow body, preferably formed of rubber and either round or ovoid in shape. Both ends of this body are provided with openings 50 that are surrounded by marginal beads 11 and extending through the opening at

the lower end of said body is a short tubular member 12, the inner end of which is closed by a plate 13, the central portion of which is perforated as designated by 14.

60 The marginal portion of plate 13 functions as a flange 15 that overlies the inner face of the corresponding rib or bead 11 and that portion of member 12 that projects through the opening in body 10 is externally threaded for the reception of a clamping plate 16 that bears directly against the outer face of the rib or bead 11 when the parts of the instrument are properly assembled.

70 Screw-seated on the outer end portion of member 12 is a cap 17 having a milled edge. The chamber within member 12 may contain various substances which are of especial advantage in the treatment of ophthalmic troubles and irregularities, although for general purposes I prefer to fill said space with a body 18 of radioactive material.

75 Projecting through the opening at the upper end of the hollow body 10 is the inner portion of a short tubular member 19 with which is formed integral a flange 20 that overlies the rib or bead 11 that is formed on the corresponding end of the body 10. 80 That portion of the tubular member 19 that projects into body 10 is threaded for the reception of a ring-shaped clamping nut 21 that engages the inner face of the corresponding bead or flange 11.

85 Rigidly fixed in any suitable manner on the outer end of tubular member 19 is a hemi-spherical cup-shaped applicator 22 that is formed of suitable material such as metal, hard rubber, celluloid, or the like, 90 and arranged on the tubular member 19 between the inner end of this applicator and the flange 20 is a disk 23 having a milled edge and said disk being mounted so that it will rotate freely upon said tubular member 19.

100 Loosely arranged on the tubular member 19 between the flange 20 and rotatably mounted disk 23 is a ring 24 to which is connected one end of a short chain or cable 25 and the free end thereof carrying a stopper 105 26 that is adapted to enter the outer end of the tubular member 19 while the device is not in use.

110 When my improved ophthalmic instrument is utilized for massaging the eye ball and its muscles, the applicator 22 is posi-

- tioned directly over and against the front portion of the eye and disk 23 is engaged between the thumb and finger of one hand while the thumb and fingers of the other hand engage the milled edge of cap 17. The thumb and fingers that engage the disk 23 retain the instrument in proper position for operation and by rotating cap 17 first in one direction and then in the reverse direction, 5 intermittent rotary motion will be imparted to the entire instrument with the exception of the disk 23, and thus the eye ball and its muscles are gently massaged with a vibratory rotary motion which is highly effective 10 and beneficial in the treatment of all forms of muscle imbalance as well as for the relief of congestions, inflammations, and the like.

During the oscillatory rotary motion all contracted muscles are stretched, thereby 20 bringing about a normal condition of such muscles and bringing about relief of the various unnatural conditions that result from muscle imbalance.

The device may be used as an ordinary 25 eye cup for the purpose of washing and cleansing the eyes and likewise for applying to the eyes a cleansing or healing agent such as a boric acid solution. By filling the cup 12 with radioactive material and filling the collapsible hollow member 10 with water before the instrument is used, the highly beneficial results of radium treatment to the eyes may be obtained. By the use of radioactive material in the instrument new and 35 healthy tissues are created and at the same time germs and diseased tissue are destroyed.

For the treatment of myopia or near-sightedness the instrument is filled with water and applied to the eye and when the wall of 40 member 10 is slightly collapsed a corresponding amount of pressure through the water will be applied directly to the front central portion of the eye ball and the cornea thereon; thus tending to shorten the eye ball and 45 consequently correcting the unnatural conditions that result in near-sightedness.

For far-sightedness the instrument may be used so as to produce suction on the front portion of the eye ball, thereby tending to 50 lengthen the same and consequently relieving the unnatural conditions.

Thus it will be seen that I have provided an ophthalmic instrument that is relatively simple in construction, capable of being 55 easily and cheaply produced and which may be readily manipulated for the purpose of imparting pressure, suction, and oscillatory massage to the eye ball and its muscles for the purpose of correcting various ailments 60 and abnormal conditions. The instrument

is constructed so that it may be used as an ordinary eye cup for cleansing the eye or for the application of healing solutions thereto, and the arrangement of a perforated container in the base of the instrument enables 65 the user of the instrument to obtain the beneficial results that arise through the use of a healing agent such as radioactive material.

Obviously the cup-shaped applicators 22 70 may be made in various sizes and interchangeably used on the outer end of tubular stem 19 and the outer edges of said applicators, or the edges that are directly applied to the eye may be either round or oval in 75 shape.

It will be understood that minor changes in the size, form and construction of the various parts of my improved ophthalmic instrument may be made and substituted for 80 those herein shown and described without departing from the spirit of my invention, the scope of which is set forth in the appended claims.

I claim as my invention:

1. In an ophthalmic instrument, a collapsible hollow member, a perforated container located in the base portion of said hollow member, an externally arranged cap for said perforated container, a stem projecting from the upper end of said hollow collapsible member, a disk mounted for rotary movement upon said stem and a cup-shaped applicator carried by the outer end of said stem. 90

2. An ophthalmic instrument comprising 95 a collapsible hollow member, a stem projecting from one end of said hollow member, a cup-shaped applicator carried by said stem, a disk mounted for rotary motion on said stem between the collapsible member and applicator and a perforated container detachably arranged in the base portion of said hollow collapsible member. 100

3. An ophthalmic massage instrument 105 comprising a hollow collapsible member, a tubular stem detachably seated in one end of said container, an eye cup carried by the outer end of said stem, a disk loosely mounted on the stem between the eye cup and collapsible container, which disk is adapted to be engaged by the thumb and finger when the instrument is used, a hollow member detachably seated in the end of the collapsible container opposite from the end in which the tubular stem is seated, the inner wall of said 110 hollow member being perforated and a cap removably mounted on the outer end of said hollow member. 115

In testimony whereof I affix my signature.
FRANCIS KING.
